GIN-SAW-FILING MACHINE.

No. 831,203.

Specification of Letters Patent.

Patented Sept. 18, 1906.

Application filed August 29, 1904. Serial No. 222,589.

To all whom it may concern:

Be it known that I, ALBERT A. Wood, a citizen of the United States of America, and a resident of Atlanta, in the county of Fulton and State of Georgia, have made certain new and useful Improvements in Gin-Saw-Filing Machines; and I do hereby declare the following to be a full, clear, and exact description of the said invention, such as will enable others skilled in the art to which it appertains to make and use the same, reference being had to the accompanying drawings, and to letters of reference marked thereon, which form a part of this specification.

The invention is shown in the accompanying drawings, as follows: Figure 1 is a front view of the machine, and Fig. 2 is a side elevation thereof from the right-hand side of Fig. 1. Fig. 3 shows fragments of the main frame and the shaft of the arms which carry the reciprocating file-rods, illustrating the peculiar manner of mounting said file-rod arms. Fig. 4 is a detail from Fig. 3, showing one of the springs removed and without the fragments of the main frame and connecting elements. Figs. 5 and 6 are details also from Fig. 3, showing the eccentric bearing for said shaft. Figs. 7 and 8 are respectively side and end views of the adjustable crank for causing the reciprocation of the file-rods. Figs. 9 and 10 are respectively front and side views of the lower end of a file-rod, showing the clamping-head thereon and a file in place, and Fig. 10^a is an end view thereof. Figs. 11 and 12 are respectively plan and side elevations of the feed-pawl which engages the teeth of the saw being filed and, vibrating, intermittently rotates same. Figs. 13 and 14 are respectively side and sectional views of the connecting-rods.

In the figures like reference characters are uniformly employed in the designation of corresponding elements of construction in all the views.

This invention consists in certain combinations of mechanism and constructions whereby the machine may rest upon the space-blocks of a cylinder of assembled gin-saws, and be thereby located with proper respect to the periphery of the saws and by means of which the sharpening-files are so located as to operate in the interdental spaces and produce a sharp-pointed tooth which is approximately

circular in cross-section and with the requisite depth of interdental space and of proper angle to the radius of the saw. 55

The invention further consists of certain means whereby the sharpening-files are given a reciprocating motion, and, if the result to be obtained requires it, simultaneously a partially rotary or rolling motion, the files at the same time being given a yielding pressure upon the saw and being provided with means whereby a slight lateral movement of the files in the plane of the saw is produced to 60 permit the settling of said files into the interdental spaces, and means for elastically controlling or permitting this slight adaptability, and, further, in producing a substantially positive intermittent motion of the cylinder 65 of saws rotarily and for lifting the files out of the interdental spaces during such movement, and, further, in certain other devices whereby the files may be adjusted to suit the exact pitch distance of teeth, and other details which will be hereinafter explained. 75

A is the center leg of the machine, which is provided with oppositely-projecting bars or arms *a*, above which it is prolonged by a vertically-slotted portion *a'*. 80

*a*² represents legs movable longitudinally of the arms *a*, whereon they may be tightened by means of screws *a'*.

The downwardly-projecting portion of the center leg A and the legs *a*² at their lower 85 ends are bifurcated to fit the space-blocks between the saws, and the leg A should be of such thickness as will fit between the saws, and so center the machine over the saw which is to be operated upon. 90

In the face of the upwardly-projecting portion *a'* are vertical slots for the screw *b*, and substantially centering upon said slots is formed a vertical guideway, and in this guideway is seated so as to be vertically adjustable 95 an angle-plate B, which is provided with horizontal slots through which pass the screws *b'*, which secure the main frame C of the machine in position. By reason of the slots in the upwardly-projecting part *a'* of the leg A and the horizontal slots in the forwardly-projecting portion of the angle-block B adjustment of the head C and the operative parts carried thereby may obviously be had respectively to 100 and from the periphery of the saw and relatively to its radius, whereby the machine may 105

be adusted for larger or smaller saws or space-blocks and to different angles of teeth relatively to the radius.

- The "main frame" of the machine, so called because it carries all of the operative elements, consists of a central web lying vertically against the forwardly-projecting flange of the angle-plate B and being provided near its bottom with a lug c' , transversely perforated, and at its top by a housing c^2 , surmounted by a grip-handle c^3 . About the middle at its back are two oppositely and laterally projecting lugs c^4 and a forwardly-projecting boss c^5 .
- c^6 is a face-plate which forms the complement of the housing and has a downwardly-projecting member, which rests upon the forward extremity of the boss c^5 , to which and to the edge of the housing c^2 it is firmly secured by screws. On said lower projection of said face-plate c^6 are lugs c^7 , situated correlative with the lugs c^4 and conjunctively therewith forming supporting elements for the shafts of the vibratable file-rod arms.
- Mounted rotatably in the lateral extremities of the housing c^2 are the shafts d of the cranks D, bearing pinions within the housing, the said cranks D being mounted upon opposite ends of their respective shafts d , whereby the crank proper of one shaft is at the front of the machine (left-hand side, Fig. 2) and the crank proper of the other shaft is at the back of the machine. (Right-hand side, Fig. 2.)
- E is the main gear or spur wheel of the machine and is constantly in mesh with the pinions on the shafts d , its shaft e being mounted in suitable journal-bearings in the main frame C and the face-plate thereof and being rotatable by a hand-crank or pulley attached outside of the face-plate. On the back side of the spur-wheel E is a cam e' of the type known as "crown-cams" and which is the feed-cam and should be duplicated in proportion to the desired interval of the feed relatively to strokes of the file. On the face or front of the spur-wheel E is a disk cam e^2 , which is provided with lugs e^3 , Fig. 1, and which is called the "lift-out" cam, inasmuch as it lifts the files from the interdental spaces, and should be so constructed and timed relatively with the feed cam or cams e' as to produce the required divergence of the points of the files very shortly after the commencement of the forward partial rotation of the cylinder of saws under the action of the feed mechanism and to allow the files to drop into the next successive interdental space just before the cessation of such feeding movement.
- This last of functions is for the purpose of keeping the files, which are constantly reciprocating, in working contact with the saw as long as possible, the slight fore-and-aft flexure of the file-carrying elements permitting

the files to follow the saw slightly in its forward movement and to adapt themselves when returning to the interdental space to the immaturely-fed position of the latter, as will be hereinafter specified.

To provide for the intermittent partial rotation of the saws, I have provided a lever F, spring-pressed to retraction by a coil-spring f and oscillatably mounted upon the frame C by a shoulder-screw f', which acts as a fulcrum, and through a series of holes therefor in the lever F, I provide for a variation of the relative lengths of the lever members, and hence a varying stroke of the pawl f", which is loosely secured to the lower end of the said lever F and carries a knife f³ upon its upper side, ground upon its forward edge to fit the teeth-spaces and slotted for purposes of adjustment, whereby it may be made to bring the saw into such position rotarily at each successive feeding as will permit the files to drop into the tooth without abnormal adjustment. A roller f⁴ on the upper end of the lever F is constantly in contact with the working face of the crown-cam e'. The spring f, hereinbefore mentioned, is hooked onto an arm f⁵ of the lever F at one end and a stud f⁶, screwed into the boss c⁵ at its other end.

Referring to Figs. 1 to 6, inclusive, G represents what I term the "file-rod arms," because they journal the reciprocating file-rods. These file-rod arms carry on each end journal-boxes g, in which are set removable bushings g', fitting the file-rods g², which latter carry the clamps g³ upon their lower ends, which will be hereinafter described. One of the file-rod arms G—the one shown at the right hand in Fig. 1—is situated on the front of the machine, while the other is situated near the back of the machine in such position that the axes of the said journal-bearings thereon will converge downwardly, so that both files will work at a proper angle to the teeth of the saw and at a distance of from two to seven teeth, say, on the periphery of the saw apart. These file-rod arms are partially rotatably mounted by securing them upon shafts or pintles g, which are indirectly mounted by their ends on the lugs c⁴ and c⁷ aforesaid. Upon reference to Figs. 3 to 6, inclusive, especially the two first named, the construction will be better understood. Set in the lug c⁴ is a stud g⁵, held in place therein by a screw g⁶, passing through the lug c⁴ and into the said stud. Upon the shaft g⁴ is a collar g⁷, and the forward end of the said shaft is provided with a pivot g⁸, g⁹ being an eccentric rotatably mounted in the lug c⁷ and having an eccentric seat therein for the pivot g⁸. Closely encircling the stud g⁵ and the end of the shaft g⁴ is a coil-spring g¹⁰, which should be a driving fit on each. Surrounding and inclosing said spring g¹⁰ is another coiled spring g¹¹, coiled in the opposite

direction and acting between abutments consisting of the lug c^4 and the collar g^7 to press the shaft g^4 forwardly, so as to hold its pivot g^8 in the seat in the eccentric g^9 . The springs 5 at the back end of the shafts g^4 act to permit a motion of the file-rod arms in the plane of the saw, same being practically fulcrumed upon the pivot-bearing in the eccentric g^9 , thereby permitting the lap of function here- 10 before mentioned of the feeding mechanism and the files and also removing such rigidity of the files as would prevent their accommodating themselves to variation of interdental distances which might be produced and do exist in saws previously filed 15 by hand or machines having unreliable feed mechanisms. The relative distance between the files, which may be changed so as to adapt them to varying pitch distances of the saw-teeth, is provided for in the eccentric mounting of the forward ends of the shafts g^4 . A partial rotation of one of eccentrics g^9 obviously swings the shaft g^4 upon a fulcrum consisting of the springs g^{10} and g^{11} , causing a 20 correlative movement of the axis of the file-rod g^2 and causing the files when this adjustment has been made to drop with certainty into the proper interdental space when the feeding of the saw has been accomplished, 25 with the files lifted from contact therewith. Screws g^{12} serve to secure the eccentrics g^9 as set. Upon the upper ends of the file-rod arms are adjustably secured roller-arms g^{13} , the rollers g^{14} of which contact with the edge 30 of the disk-cam e^2 and are caused to diverge by the projections e^3 thereof at a time, as aforesaid, just subsequent to the starting forward of the saw, due to the action of the feed mechanism. In the case of the front 35 file-rod arm G this arm g^{13} is secured to an integral upward projection g^{15} of said arm; but in the case of the back file-rod arm G a supplementary arm g^{16} is secured upon the correlative shaft g^4 for this purpose. As 40 shown in Fig. 1, these roller-arms g^{13} are so adjustable as to provide for a greater or lesser lifting of the files. The file-rod arms are spring-pressed divergently at their lower ends in order to press the crossed files upon 45 the saw by means of springs g^{17} , secured at one end to said file-rod arms and at the other end to a hook-block g^{18} , adjustably mounted upon a rod g^{19} , passing through the transversely-perforated lug c' of the frame C and 50 being secured therein. g^{20} represents wrists on the file-rods g^3 , by which connection is made for their reciprocation and partial rotation during same. As best shown in Figs. 9 and 10, the file-clamps g^3 are loosely se- 55 cured by a pin g^{21} , set in the rod and passing freely through a hole in a lug on said file-clamps. In the lower ends of the said file-rods are milled V-shaped grooves whose sides 60 are at a right angle to each other, so as to fit a square file. The inner face of the file- 65 clamp is at a right angle to a bisector of the angle of said groove, whereby not only may the corner of a square file be engaged and pressed into the said groove, so as to hold it rigidly, but a triangular file may also rest 70 one of its sides against the flat inner surface of the said file-clamp, and so be supported rigidly, with its corner in the angle of said groove, but without its sides touching the sides of said groove, the angle of the groove 75 being ninety degrees and the angle of the file being sixty degrees. In like manner a file with any degree of angle on its working edge may be supported in proper position to work 80 in the interdental spaces.

It is found by experience that a square file run without axial rotation between the teeth of a gin-saw will make the proper-shaped tooth, although not the ideal tooth for ginning cotton, which is a cone circular in cross- 85 section. A square file will not, however, enter the interdental space as rapidly in action as will a three-cornered file, nor can it be partially rotated upon its own axis during action to produce the rounded or needle-point afore- 90 said. The rapid deepening of the teeth by running a three-cornered file thereon without axial partial rotation is very advantageous in the preliminary cutting down of teeth worn very short or broken off by use, which 95 is the normal dull condition of gin-saws. Now in order to accommodate the machine which I have shown is capable of carrying either sort of file to the varying requirements of the premises I have provided cranks 100 D, the wrist of which is adjustable to vary its obliquity and which I will now proceed to describe. As aforesaid, the shafts d are mounted at the ends of the housing c^2 , bearing pinions d^2 and having, as best shown in 105 Figs. 7 and 8, cross-heads d^3 . This cross-head is perforated longitudinally and projects one end farther from the center of the shaft d than the other end, whereby the stroke may be made longer or shorter, as de- 110 sired, each of said ends being conical on its extremities and split, as shown in Fig. 8, whereby the collars d^4 and d^5 , provided with conical apertures, may by being pressed 115 thereon reduce the diameter of the aforesaid perforation, so as to clamp upon the pin d^6 of the L-shaped wrist-piece d^7 . To provide for this clamping of the collars aforesaid, I pro- 120 vide the end of the pin d^6 which passes through the longitudinal perforation of the cross-head d^3 with a screw d^8 , the function of 125 which is plain. The wrist d^9 is substantially at a right angle to the pin d^6 . It is plain that by loosening the screw d^8 the wrist d^9 may be partially revolved upon its pivot, the pin d^6 thus producing the desired degree or obliquity of the axis of the wrist d^9 to the axis of the wrist d . Thus, obviously, the revolution

of the wrist d^9 around the axis of the shaft d will produce a reciprocating motion of the file-rods g^9 , accompanied by a greater or less degree of partially-rotary movement and provide the peculiar movement of the file, which causes it to roll upon the back and front of adjacent teeth of the saw, with the result aforesaid. By the use of a square file without this partially-rotary motion thereof a tooth will be produced which is conical, but rectangular in cross-section, while by using a three-cornered file under the same conditions the interdental space will be deepened without a correlative reduction of the thickness of the tooth.

H is the pitman, which connects the wrists d^9 and g^{20} and transmits motion from the cranks to the file-rods, consisting, as shown in Figs. 13 and 14, of the connecting-rod proper, h , and bearing-boxes h' on either end thereof, all alike in construction. These bearing-boxes are cast solid and drilled to receive the wrists, a saw-cut being made in the lug thereof to fit the end of the connecting-rod h and said rod being perforated at its ends. The two lugs so formed are perforated with a larger hole, a shouldered pin h^2 being passed through the perforation in the said rod h , with its larger portion fitting and lying within the perforation of one of the lugs h^3 of the bearing-box. The reduced portion of the said pin h^2 is then firmly fastened and secured to the rod h , preferably by being "staked" therein, and a collar h^4 is placed around said reduced portion within the unoccupied opening in the other lug, and the end of the reduced portion of the pin h^2 is riveted to hold same in place. This novel construction is necessary at this point by reason of the double stress placed upon this joint by the reciprocating and partially-rotary motion transmitted thereby. It will be seen by this construction a relatively larger pin is provided than could be otherwise obtained, and its becoming loose, and consequent reduced efficiency and working out, is obviated by its close connection with the connecting-rod. The double bearing of the end of the rod itself between the lugs and on the pin provides a bearing which is more lasting than any other practicable form.

By loosening the screw g^{22} , Fig. 1, the rod g^{19} will shift endwise and exactly equalize the pressure on both files, producing, with files in their usual equal condition of sharpness, uniform work on both sides of the saw.

Having thus described my invention, what I claim as new, and desire to secure by Letters Patent of the United States, is—

60 1. In a gin-saw-filing machine, a frame and means for supporting same in operative relation to the gin-saw, a shaft mounted on said frame by its ends, an eccentric bushing forming the means for mounting one end

thereof, a file-rod arm carried by said shaft, a file-rod adapted to carry a file on its extremity and mounted slidably in said file-rod arm, and means for causing said file-rod to reciprocate therein and for pressing same into operative position elastically.

2. In a gin-saw-filing machine, a frame and means for supporting same in operative relation to the gin-saw, a stud set in said frame, a file-rod arm comprising the arm proper with file-rod bearings thereon and a shaft, the one end of said shaft being loosely mounted with its other end in juxtaposition to said stud and a coil-spring coiled closely upon said stud and shaft end, a file-rod slidably mounted in the bearings on said file-rod arm and means for producing a reciprocatory movement of said file-rod and for securing a file to the extremity of said rod.

3. In a gin-saw-filing machine, a frame and means for supporting same in operative relation to the gin-saw, an eccentric bushing set in said frame, a stud set in said frame in opposition to said eccentric bushings, a file-rod arm comprising the arm proper with file-rod bearings thereon and a shaft therein, one end of said shaft being loosely mounted in said eccentric bushing with its other end in juxtaposition to said stud and a coil-spring coiled closely upon said stud and shaft end, an abutment on said shaft and a larger coil-spring surrounding said first-named spring with its ends in contact with said abutment and the frame, a file-rod slidably mounted in the bearings on said file-rod arm and means for producing a reciprocatory movement of said file-rod and for securing a file to the extremity of said rod.

4. In a gin-saw-filing machine, a frame and means for supporting same in operative relation to the gin-saw, a rod mounted in suitable bearings and adapted to have a spiral motion therein, and a crank comprising a shaft with a cross-head thereon, longitudinally perforated, and a wrist-pin, the laterally-projecting arm of which is inserted in said longitudinal perforation so as to be axially rotatable therein to adjust the wrist-pin to and from parallelism to the axis of said shaft and means for locking it in such adjustment and a pitman connecting said wrist-pin and said rod.

5. In a gin-saw-filing machine, a frame and means for supporting same in operative relation to the gin-saw, a rod mounted in suitable bearings and adapted to have a spiral motion therein, and a crank comprising a shaft with a cross-head longitudinally perforated thereon, split and cone-shaped at its ends, an L-shaped wrist-pin the laterally-projecting arm of which is inserted in said longitudinal perforation, means for locking it therein consisting of conically-bored collars fitting said laterally-projecting arm and

placed thereon so as to embrace the cone-shaped ends of said cross-head and a screw set substantially axially in said laterally-projected arm and adapted to converge said 5 collars upon said cone-shaped ends, and a pitman connecting said wrist-pin and said rod.

In testimony whereof I hereunto affix my signature in presence of two witnesses.

ALBERT A. WOOD.
